UNITED STATES PATENT OFFICE.

GEORGE T. JOHNSON, OF NEW YORK, N. Y.

DISPENSING-FIXTURE.

1,399,432.

Specification of Letters Patent.

Patented Dec. 6, 1921.

Application filed March 1, 1920. Serial No. 362,449.

To all whom it may concern:

Be it known that I, GEORGE T. JOHNSON, a citizen of the United States, residing at New York city, in the county of New York, State 5 of New York, have invented a certain new and useful Improvement in Dispensing-Fixtures, of which the following is a specification, reference being had therein to the accompanying drawings.

10 This invention relates to dispensing apparatus for roll material; more especially to apparatus of the class used for dispensing short lengths of toilet paper and paper toweling from wound rolls of continuous strip 15 or web material, usually weakened at intervals on transverse lines by slits or perforations. More particularly, it relates to dispensing fixtures of the class in which the roll-support has combined therewith devices 20 acting by friction to retard the unwinding revolution of the roll produced by a pull on the outer end of the strip or web, so that the resistance to turning that is due to the friction shall operate to cause the strip or 25 web to break or tear across, as for instance at a line of weakening.

One general object of the invention is to provide dispensing fixtures of such class of improved construction and adapted to handle 30 commercial roll packages of a variety of widths found in the market. Another is to provide improved fixtures of the said class having the friction devices thereof adjustable to suit rolls of different widths. Other 35 objects thereof are to simplify the construction, reduce cost of manufacture, and produce a strong, durable and practical fixture, one that will operate satisfactorily, and one that is simple and easy of manipulation in 40 making application of a fresh roll thereto.

The illustrative embodiment of the invention which is shown in the drawings is the preferred form of embodiment of the features of the invention. In its general 45 construction, the dispensing fixture shown is of the well-known type having opposite side arms which are relatively movable toward and from each other for the purpose of closing and opening the fixture, roll-supporting 50 means in connection with said arms adapted to occupy the central opening of a wound roll of paper, and disconnectible means for connecting said arms and locking them in closed relations for supporting the said roll. 55 In conformity with the invention, I combine

with the said arms and roll-supporting means improved spring-actuated friction-devices adapted to coöperate with wound rolls of different widths within the capacity of the fixture, and means for adjusting 60 the said friction devices to suit rolls of different widths.

In the drawings,—

Figure 1 is a plan view of the illustrative embodiment aforesaid, partly in section. 65

Fig. 2 is a front view thereof partly in section.

Fig. 3 is a sectional view on the line 3—3 of Fig. 2.

Fig. 4 is a view in horizontal section on 70 line 4—4 of Fig. 3.

Fig. 5 is a face view of the friction-plate, shown separately.

Having reference to the drawings,—

The said embodiment has a wall-plate or 75 base 1 which is shown as provided at its opposite ends with integrally-formed hooks 2, 2, within which latter the pintles 3, 3, upon the opposite side arms 4, 5, are retained when the fixture is in position upon a wall, 80 to provide in well-known manner for hinging the said supporting arms 4, 5, to the said wall-plate or base with capacity to be swung away from each other so as to open the fixture for the introduction of a full roll, and 85 then toward each other to close the fixture again. The more immediate roll-supporting means comprises cylindrical hubs 6 and 6^a projecting toward each other from the inner sides of arms 4, 5, the said hubs being of 90 a diameter suitable to enter within the cores to be found in the roll-packages which the fixture is designed to receive. The hub 6 carries a friction-plate constituted by a washer or partly annular disk 7 which is de- 95 signed to be pressed by a spring 8 against the end of the roll 9, shown by dotted lines in Fig. 2, of web material applied to hubs 6, 6^a. Thereby the roll is compressed endwise between said plate or washer 7 and the oppo- 100 site supporting-arm 5 so as to provide a sufficient frictional resistance to turning of the roll to cause the strip or web to break at a line of transverse weakening in the material drawn off from the roll by a pull upon 105 the outstanding free end of the strip or web. Preferably the plate or washer 7 is held from turning with the roll, which is effected in the present instance by making the hub 6 hollow and with two diametrically opposite 110

- longitudinal slots 6^x, 6^y, into which enter two radially-disposed cross-pieces or spokes 7^x, 7^y, joining the annular outer portion of said plate or washer 7 which surrounds the collar 6 with the central portion 7^y thereof within said hub 6, surrounding the spindle 10. The spring 8, (Fig. 2) is an expanding spiral spring. It occupies the interior chamber of hub 6, and is confined between the closed outer end-wall of said chamber and the said central portion 7^y of the plate or washer 7. The said spring serves to hold the plate or washer against the end of the roll 9 tightly enough to provide the requisite friction and resistance to the turning of the roll. The spindle 10 is fixed by its outer end to arm 4, and extends axially of hub 6 inward into proximity with the opposite supporting arm 5. In this instance the spring 8 surrounds the said spindle.
- A simple and effective means of locking the said supporting arms 4 and 5 in closed relation is illustrated in Fig. 2, in which the spindle 10 is hollowed out throughout the enlarged portion comprising about two-thirds of its extent, and has fitted therein a longitudinally extending axial bolt 11 slidably mounted therein and pressed endwise outward by an expanding spiral spring 13 occupying the chamber within the spindle 10. The spring projects the bolt to the extent allowed by the stop or pin 14 projecting radially from the bolt and traveling in a longitudinal lateral slot in the wall of the tubular portion of said spindle 10. Said bolt 11 is adapted to enter and fit closely within a hole 12 in the hub 6^a upon arm 5. It will be observed that as arm 4 and its rigidly mounted spindle 10, and arm 5 with the hole 12, must travel in circular paths in swinging outward and away from each other, no spreading motion will be possible while the bolt 11 is in place in the hole 12 as in Fig. 2, because the slightest outward movement of either arm will cause the bolt to cramp or bind within the hole 12. To provide for opening the fixture, the bolt must be withdrawn from hole 12, which may be accomplished, when the spindle 10 is in an uncovered state, by pushing upon pin 14 toward the left. This locking device fixes the supporting arms in their closed position rigidly and without play, fastens easily, is securely hidden away from meddling fingers so long as any portion of the roll, or its core, is left upon the spindle, and may easily be unlocked after the spindle 10 has been uncovered by the removal of the roll-material and core.
- The action in locking is practically automatic, all that is required being to swing the two arms 4, 5, inward toward each other so that the inner end of hub 6^a shall encounter the outer end of the bolt 11 and press the bolt back within spindle 10 until the swing-

ing movement of said arm causes hole 12 to align itself with the bolt. The bolt thereupon will be pushed into the hole by the action of spring 13. The entry of the bolt into the hole, thus occasioned, will effect the locking.

A feature of the invention is the means of adjusting the friction devices to suit rolls of different widths within the capacity of the fixture. Commercial roll packages varying more or less in width are found in the market. For instance, some are four inches wide, some are a little under four and one-half inches wide, and some are four and three-fourths inches wide. For the purposes of the adjustment, the spindle 10 is screw-threaded for a portion of its length, and a wing-nut 17 is placed thereon adjacent the inner end of the hub 6, at a point where it will be exposed to access when the fixture is empty, for convenience in manipulating the same in making adjustments, but will be covered and hidden by a roll occupying the fixture. A sleeve 16, surrounding the spindle between the wing-nut and the central portion of the friction-plate or washer 7 serves as a filler, it extending as shown in Fig. 4 within the hollow of hub 6 into engagement with the said central portion of friction-plate or washer 7. The wing-nut 17 constitutes an adjustable stop to limit the travel of friction-plate or washer 7 inward upon the hub 6 under the action of spring 8 when the fixture is empty. Through adjustment of the wing-nut, the position occupied normally by the friction-plate or washer 7 upon hub 6 while the fixture is empty may be made to correspond substantially with the width of roll intended to be applied to the fixture, and in addition, the compression to which a roll applied to the fixture is subjected in the closed and locked condition of the latter may be regulated so as thereby to control the frictional resistance to the turning movement of the roll.

Preferably, and as illustrated in Fig. 4, the spring 8 is wound in the form of a tapering helix, the successive coils or turns thereof being so proportioned that they are adapted to fit one within another as the spring is compressed, and so that when it is fully compressed they all occupy substantially a single plane; in such condition the spring has the form of a flattened spiral. Thereby, the lateral dimensions of the fixture are enabled to be kept at a minimum.

In applying the principles and features of the invention, the construction of the fixture may be varied more or less.

The wing-nut 17, in addition to serving as a means of adjusting the position of the friction-plate or washer 7 to correspond approximately with the positions of the adjacent ends of supply rolls of different lengths, and to adjust more or less the action

of the said friction-plate or washer upon the roll, also constitutes a convenient means for enabling the friction plate or washer to be set back and held in inoperative relations 5 with the roll-end, out of engagement therewith. This enables the frictional resistance to the turning of a roll to be dispensed with, when desired.

What is claimed as the invention is:

10 1. A dispensing fixture for continuous web material wound in roll form, having a roll support adapted to enter the central opening of a roll, and a spring-actuated friction-plate adapted to act against an end 70

15 of a roll applied to said roll-support, movable lengthwise of the roll-support, and engaging with the roll-support so as to be held thereby from turning with the roll.

20 2. A dispensing fixture for continuous web material wound in roll form, comprising a longitudinally-slotted hollow roll-support adapted to enter the central opening of a roll, a friction-plate mounted in connection with said roll-support for movement against an end of the roll and engaging in the slot or slots of the roll-support so as thereby to be held from turning with the roll, and a spring within the roll-support which actuates said friction-plate against 90

30 the roll-end.

35 3. A dispensing fixture for continuous web material wound in roll form, having a roll-support adapted to enter the central opening of a roll, and a spring-actuated friction-plate adapted to act against an end of a roll applied to said roll-support, movable lengthwise of the roll-support, and engaging with the roll-support so as to be held thereby from turning with the roll, and a stop 100

40 which limits the inward movement of the said friction-plate, adjustable to suit rolls of different widths.

45 4. A dispensing fixture for continuous web material wound in roll form, comprising opposite arms which are relatively movable to permit of the application of a roll, means for supporting a roll between the said arms, a spring-actuated friction-plate which acts against an end of the roll to oppose the 110

50 unwinding revolution thereof, and a stop to limit the inward movement of said plate, adjustable to correspond substantially with different roll-widths.

55 5. A dispensing fixture for continuous web material wound in roll form, comprising opposite arms which are relatively movable to permit of the application of a roll, said arms having hubs to enter the central opening of said roll, a spring-actuated friction-plate carried by one of said hubs and adapted to act against an end of the roll to oppose through frictional engagement with such end the unwinding revolution of the roll and means for locking said friction- 120

60 plate from rotating in unison with the roll.

6. A dispensing fixture for continuous web material wound in roll form, comprising opposite arms which are relatively movable to permit of the application of a roll, said arms having hubs to enter the central 70

opening of said roll, a spring-actuated friction-plate disposed coaxially with the roll to oppose the unwinding revolution thereof through frictional engagement with an end of the roll, and means for locking said friction-plate from rotating in unison with the roll.

7. A dispensing fixture for continuous web material wound in roll form, comprising opposite non-rotating arms which are 80 relatively movable to permit of the application of a roll, said arms having hubs to enter the central opening of said roll, a spring-actuated plate movable relative to one of said hubs, which bears against the 85 corresponding end of the roll and holds the other end thereof in frictional contact with the adjacent arm so as to oppose the unwinding revolution of the roll and means for preventing rotation of said plate relative to 90

the said hub.

8. A dispensing fixture for continuous web material wound in roll form, comprising opposite non-rotating arms which are relatively movable to permit of the application 95 of a roll, said arms having hubs to enter the central opening of said roll, a spring-actuated plate disposed coaxially with the roll, movable relative to one of said hubs, which bears against the corresponding end 100 of the latter so as to hold the other end thereof in frictional contact with the adjacent arm to oppose the unwinding revolution of the roll, and means for preventing rotation of said plate relative to the said 105 hub.

9. A dispensing fixture for continuous web material wound in roll form, comprising opposite arms which are relatively movable to permit of the application of a roll, 110 said arms having hubs to enter the central opening of said roll, one of said hubs provided with longitudinal slots, and a spring-actuated friction-plate disposed concentrically with the said hub, adapted to oppose the unwinding revolution of the roll, and having spokes working in said slots.

10. A dispensing fixture for continuous web material wound in roll form, comprising opposite non-rotating arms which are 120 relatively movable to permit of the application of a roll, said arms having hubs to enter the central opening of said roll, a spindle carried by one of said arms and provided with means for locking engagement with the 125 opposite arm, a spring-actuated friction-plate disposed coaxially with relation to said spindle movable relative to one of said hubs and adapted to coact with friction means at the opposite end of the roll to op- 130

pose the unwinding revolution of the roll, and means for preventing rotation of said friction plate relative to the said hub.

11. A dispensing fixture for continuous web material wound in roll form, comprising opposite arms which are relatively movable to permit of the application of a roll, said arms having hubs to enter the central opening of said roll, a spindle carried by one of said arms and provided with means for locking engagement with the opposite arm, and a spring-actuated friction-plate movable lengthwise of said spindle, and a stop for said friction-plate adjustable to accommodate rolls of different widths.

12. A dispensing fixture for continuous web material wound in roll form, comprising opposite arms which are relatively movable to permit of the application of a roll, said arms having hubs to enter the central opening of said roll, a spindle carried by one of said arms and provided with means for locking engagement with the opposite hub, a friction-plate movable lengthwise of said spindle, a stop defining the extent of inward movement of said friction-plate, and an expanding spring acting inwardly against the friction-plate, in the form of a tapering helix adapted to be compressed

into a flattened spiral substantially in a single plane.

13. A dispensing fixture for continuous web material wound in roll form, having a roll support adapted to enter the central opening of a roll, a spring-actuated friction-plate movable lengthwise of the roll-support and adapted to act against an end of a roll applied to the latter, and means for holding said friction-plate in inoperative relations with the roll-end, out of engagement therewith.

14. A dispensing fixture for continuous web material wound in roll form, having a roll support adapted to enter the central opening of a roll, a spring-actuated friction-plate movable lengthwise of the roll-support and adapted to act against an end of a roll applied to the latter, and a screw-threaded member adapted to be adjusted into a position holding said friction-plate in inoperative relations with the roll-end, out of engagement therewith.

In testimony whereof I affix my signature in presence of two witnesses.

GEORGE T. JOHNSON.
